UNITED STATES PATENT OFFICE.

AUGUST C. SCHWAGER, OF NEW YORK, N. Y., ASSIGNOR OF ONE-HALF TO JULIUS HOLLANDER,
OF BOSTON, MASSACHUSETTS.

THERMAL GAS-CUT-OFF DEVICE.

No. 901,197.

Specification of Letters Patent.

Patented Oct. 13, 1908.

Application filed April 13, 1908. Serial No. 426,633.

To all whom it may concern:

Be it known that I, AUGUST C. SCHWAGER, a citizen of the United States, and a resident of New York, in the county of New York and State of New York, have invented certain new and useful Improvements in Thermal Gas-Cut-Off Devices, of which the following is a specification.

This invention relates to a thermal gas cut-off device for shutting off the supply of gas to house meters and piping in case of fire, when the temperature in the vicinity of the cut-off device rises to a point where it will melt a fusible element having a low melting point, and it is especially adapted to cut off the supply of gas from city mains to a house meter when the temperature in the vicinity of the meter rises high enough to melt any portion of the meter casing.

10 In the accompanying drawings I have illustrated one embodiment of the invention, in which

Figure 1 is a central sectional view through the valve-casing of the device, illustrating the valve in its open position, in which it is held by the fusible element. Fig. 2 is a similar view showing the valve forced to its seat by the release of a valve-actuator, which is normally held under restraint. Fig. 3 is a transverse section of the valve and valve-casing, the section being taken in the line 3—3, Fig. 1.

Similar characters designate like parts in all the figures of the drawing.

15 The thermal gas cut-off embodying my invention contains preferably a tapered plug valve, such as 2, working in a valve-casing, such as 3, having a tapered seat. The valve-casing 3 has the usual threaded inlet and outlet openings, such as 4 and 5, the former of which will generally be in direct communication with a street main leading from the source of supply, connection being made to the main through suitable piping, while the outlet 5 will be in communication through similar piping with the ordinary meter. It will be noticed that the inlet and outlet openings are connected by a passage which intersects the tapered seat of the casing, dividing the valve-seat into two portions, one of which is indicated by 6 and the other by 6'. At the lower end of the valve-casing a plug, such as 7, may be placed for the purpose of permitting access to the interior of the casing for the purpose of re-

moving accumulations of hydrocarbons, etc. This plug 7 is screw-threaded into the bottom of the casing as shown, so as to fit tightly therein and prevent escape of gas. The upper end of the tapered opening in the casing may be closed gas-tight in any suitable way, as for example, by means of a threaded cap, such as 8, which in this case forms a part of a cylinder 9 in which the stem of the valve 2 works. The stem of this valve is indicated at 10. The upper part of the valve-casing is externally threaded to engage corresponding internal threads in the cap 8, which cap and the upper end of the casing are preferably formed with ground seats, such as 11, for the purpose of making the connection gas-tight without using packing.

20 At the upper end thereof the cylinder 9 is closed in a manner similar to that just described by a threaded cap 12 which also has internal threads engaging external threads at the upper end of said cylinder. A gas-tight fit of the cap on the upper end of the cylinder may be made in a manner substantially similar to that just described in connection with the cap 8. The ground annular seats of the cap 12 and the coacting end of the cylinder 9 are indicated at 13.

25 The valve-stem shown is of two diameters, the upper portion thereof being reduced and being encircled in this instance by a strong coiled spring 14 constituting a power device normally tending to close the valve, but which is normally held in restraint in a manner which will be hereafter described. This spring 14 rests at its lower end against the shoulder 15 of the valve-stem and at its upper end bears against a packing-ring, such as 16, provided for the purpose of preventing escape of gas through the opening in which the valve-stem works. This packing is held firmly in place by the spring 14.

30 Normally the valve 2 is held open by a device which embodies a fusible element having a low melting point. The means for holding the valve normally open may be of any suitable type, but the fusible element will generally be a connector of soft solder properly combined with the valve to hold the same securely in the open position. Preferably the means for holding the valve open will be connected with manual valve-operating means secured to the stem of the valve, the construction shown being one in which

the manual operating means consists of two handles 17 and 18 pivoted to the upper end of the valve-stem and connected by a threaded bar, such as 19, consisting of two parts 5 made of metal having a relatively high melting point, and a third part or fusible element joining the two main parts. The fusible element is indicated at 20 as a piece of solder of the proper size and strength connecting 10 the threaded portions of the bar 19, the ends of which have stop-nuts, 21 and 22, for holding the handles 17 and 18 in the desired position. The lower ends of these handles are formed in this case with curved cam surfaces 15 which permit the valve-stem and thereby the valve to be raised readily. The normal positions of the parts are shown in Fig. 1. The positions of the parts in case of a fire when the fusible element 20 has been melted are indicated in Fig. 2. It will be noticed that the tapered plug gas valve 2 has been forced downward by the spring 14, and that the tapered surface of the valve is in close contact with the coating tapered 20 surfaces 6 and 6^a of its seat, cutting off communication between the main and the meter. The tapered surfaces of the valve and its seat in the casing are both ground in order that there may be no leakage of gas past the 25 valve after the latter has been closed. The valve itself is preferably bored out, as shown at 23, for the double purpose of providing a space into which accumulations of hydrocarbons in the casing may be forced and to 30 enable the lower end of the valve to be tapered to a sharp edge, such as 24, which will assure its cutting through any such accumulations and finding a positive seat when the spring is released.

40 It will be obvious that the normal positions of the parts shown in Fig. 1 will remain unchanged until the connector 20 is melted, when the force normally holding the valve open being removed the spring will 45 come into action and effect a positive closing of the valve to the position shown in Fig. 2. By means of my invention the added danger of gas escaping in houses, stores, etc., when a fire occurs, is obviated, as the thermal cut-off device will automatically cut off 50 the supply to the meter and prevent escape of gas into the house or other building even if the piping is melted or broken on the house side of the meter.

55 What I claim is:

1. A thermal gas cut-off device, embodying a valve-casing connected with a source of supply of illuminating gas and having a ground tapered seat, a long ground tapered 60 plug gas valve in said casing, a valve-stem projecting from said valve, guiding means in which said stem is positively guided and freely movable throughout the movement of

the valve from its open to its closed position, a power device normally tending to close 65 said valve, and means for normally holding said valve open, said means embodying a fusible element clear of said valve-stem and having substantially all of its surfaces directly exposed and also having a low melting 70 point.

2. A thermal gas cut-off device, embodying a valve-casing connected with a source of supply of illuminating gas and having a ground tapered seat and also having a cleaning opening at the bottom of the casing, a removable plug tightly fitting said opening for permitting cleaning of the valve-casing, a ground tapered plug gas valve in said casing having at its small end an opening forming a knife-edge around said end of the valve, a power device normally tending to close said valve by movement in the direction of the valve-axis, and means for normally holding said valve open, said means embodying a fusible element having a low melting point.

3. A thermal gas cut-off device, embodying a valve-casing connected with a source of supply of illuminating gas and having a ground tapered seat, a long ground tapered plug gas valve and a valve-stem formed in one piece and one forming a continuation of the other, means for guiding said valve-stem at opposite ends thereof, a spring surrounding said stem and normally tending to close said valve and hold it to its seat, and means for normally holding said valve open, said means embodying a fusible element clear of said valve-stem and having substantially all of its surfaces directly exposed and also having a low melting point.

4. A thermal gas cut-off device, embodying a valve-casing connected with a source of supply of illuminating gas and having a ground tapered seat, a long ground tapered plug gas valve and a valve-stem formed in one piece and one forming a continuation of the other, means for guiding said valve-stem at opposite ends thereof, a spring surrounding said stem and normally tending to close said valve and hold it to its seat, means including a pair of pivoted handles connected to said valve stem for moving the valve away from its seat in opposition to the power of the spring, and connecting means joining said handles for normally holding said valve open, said means embodying a fusible element having a low melting point.

Signed at New York, in the county of New York, and State of New York, this 11th day of April, A. D. 1908.

AUGUST C. SCHWAGER.
